BY Tracy Paul,
ATTORNEYS.

UNITED STATES PATENT OFFICE.

JOAH BROGDEN, OF MELROSE PARK, PENNSYLVANIA, ASSIGNOR TO DAVID LUPTON'S SONS COMPANY, OF PHILADELPHIA, PENNSYLVANIA, A CORPORATION OF PENNSYLVANIA.

WINDOW.

Application filed March 10, 1927. Serial No. 174,319.

This invention relates to windows, and more particularly to the type wherein the sashes are pivotally hung to the supporting frames as distinguished from those in which 5 the sashes are slidable.

Amongst the objects of my invention are, to render opposite sides of pivoted sashes easily accessible for cleaning from within doors when the windows are swung open; and to 10 insure maintenance of the sashes in any position of opening against the possibility of displacement under wind pressure, without necessitating use of special locking or securing means for the latter purpose.

15 These ends I attain by provision of a novel hinge mounting, which, as the windows are opened, causes the hinged edges of the sashes to recede to a substantial distance away from the contiguous rails of the window frames 20 with provision of ample arm room in the interval; and which, although permitting ready opening or closing of the windows, offers sufficient resistance against movement of the sashes under the conditions aforesaid.

25 Other objects and attendant advantages will be readily apparent from the detailed description hereinafter of the typical embodiment of this invention shown in the drawings.

Fig. I is a fragmentary view of the outside 30 of a casement window equipped with my novel sash mounting.

Fig. II is a plan sectional view in accordance with the arrows II—II in Fig. 1.

Fig. III is a detail section taken locally as 35 indicated by the arrows III—III in Figs. I and II.

Fig. IV is a detail sectional view in accordance with the arrows IV—IV in Figs. I and II.

40 Fig. V is a perspective view showing the two interpivoting members of the sash mounting; and,

Fig. VI is a perspective view of a guide bar 45 constituting one of the elements of the mounting.

In these illustrations, the window frame is comprehensively designated by the numeral 10, and the swinging sash by the numeral 11, both being constructed from suitable metal 50 bar stock, in the present instance, of Z cross section and so proportioned that their respective rails contact and interlap as shown in Fig. IV to insure weather tightness when the window is closed. The specific type of

window structure chosen for convenience of 55 illustration in the present connection is of course to be regarded as one of many others with which the sash mounting of my invention may be used.

As herein shown, the sash mounting comprises two interpivoting members 12, 13, (Fig. V) whereof the first embodies an axially-apertured pivot ear 15 with a laterally offset depending flange 16 for attachment to the rail 11^a of the window sash 11, suitably spaced 60 holes 17 being provided in said flange to take securing screws 18, see Fig. I. From Fig. V it will also be observed that the member 13 has a bearing boss 19 with an axial pivot pin 65 tle 20 to engage the aperture in the ear 15 of 70 the member 12. The part 13 furthermore has an offset lateral extension 21 formed with a dove-tail groove 22 to engage a guide bar 23 (Fig. VI) of corresponding cross-section, secured, as shown in Figs. I and III, along the 75 underside of the upper rail web 10^a of the window frame 10 by screws 25. The sash 11 is further connected to the window frame 10 80—beyond the hinge region—by a projector link 26, having pivotal attachment at 27 with 85 said sash, and at 28, with a fixed stud taking into the outer end of the guide bar 23. It is to be understood that the parts just described are duplicated in reverse order at the bottom of the window. Now since the members 13 of the two hinge mountings employed with 90 the window are confined to sliding movement along the bars 23, it will be apparent that, as the window sash 11 is opened outwardly to the dot-and-dash line position of Fig. II, the 95 pivoted edge of the said sash 11 is caused to recede or move away from the contiguous rail of the window frame 10 under action of the links 26. As a consequence, both sides of the sash 11 are rendered accessible for cleaning of its panes or lights from within doors.

For the purpose of preventing movement of the sash 11 under wind pressure when in open position, I make provision as follows: Between the ear 15 and the bearing boss 19— 100 respectively—of the members 12, 13 of each sash mounting is interposed a friction washer 30, and a similar washer 31 applied for abutment against the lower face of the ear aforesaid. The protruding end of the pintle 105 20 is threaded for engagement by a nut 32 beneath which a split spring washer 33 is inserted. This arrangement obviously per-

mits adjustment of the frictional pressure between the contacting surfaces of the parts 15, 19 and the washers 30, 31 so as to yieldingly resist pivotal movement of the sash 11 5 to a corresponding degree, the adjusted pressure being subsequently maintained under the action of the spring washer 33. To insure the nut 32 against slipping after adjustment, the latter is provided, as shown, with a number 10 of diametrical slots for selective registry with a transverse aperture in the pintle to receive a locking cotter pin 34. The washers 30, 31 are preferably made of a material or metal different from that of the members 12, 15 13, for example of brass or bronze when said members are of iron or steel. Such a combination of metals very satisfactorily serves the purposes of my invention in actual practice without the parts undergoing appreciable 20 wear over long periods, or requiring extensive lubrication in service.

While I have herein shown my invention embodied in a window having its sash pivoted for swinging movement about a vertical 25 axis, it may obviously be used, with attainment of advantages identical to those pointed out above, in connection with windows wherein the sashes swing horizontally.

Having thus described my invention, I 30 claim:

1. A sash mounting for pivoted windows including interpivoted members, each of which comprises an apertured ear with an off-

set attaching flange, and bearing boss with a pivot pintle and dovetailed extension confined to sliding movement along parallel rails in the window frame, projector links connecting the frame and the sash to determine sliding of the pivot members incidentally to swinging of the sash, friction elements at 35 each side of the apertured ears in the sash pivots, and a spring washer for maintaining pressure upon said friction elements to yieldingly resist swinging movement of the sash.

2. A sash mounting for pivoted windows 40 including interpivoted members, each of which comprises an axial apertured ear with a lateral offset attaching flange, and a bearing boss having an axial pivot pintle and a dovetailed offset extension confined to sliding movement along parallel rails in the window frame, projector links connecting the frame and the sash to determine sliding of the pivot members incidentally to swinging 45 of the sash, friction washers of contrasting material at each side of the apertured ears in the sash pivots, a split spring washer for maintaining pressure upon said friction washers to yieldingly resist swinging movement 50 of the sash, and means whereby the tension of the spring washer can be adjusted to 55 vary the frictional pressure.

In testimony whereof, I have hereunto signed my name at Philadelphia, Pennsylvania, this 28th day of February, 1927.

JOAH BROGDEN.
